Louis Rochat,
INVENTOR.

BY *Victor J. Evans,*

WITNESS:

Mr. Ford.

ATTORNEY

UNITED STATES PATENT OFFICE

LOUIS ROCHAT, OF NEW YORK, N. Y.

PUNCHING DEVICE

Application filed August 3, 1929. Serial No. 383,256.

This invention relates to punching devices and has particular reference to a punching instrument which is removably attachable to a supporting article.

5 One of the objects of the invention is to systematize the method of punching tickets, such as are used in restaurants and like places, by providing one or more punches in certain locations, with a view to obviating the necessity of looking for a punch when an attendant wishes to register the amount of a purchase on a ticket.

Another object of the invention is the 15 positioning of a punching device at a favorable angle, so that a ticket carrying members thereon may be readily placed in the device by the fingers of one hand of an attendant, without necessitating previous manipulation of the device, the latter being 20 then ready for operation by the fingers of the same hand for punching one of the numbers to indicate the amount of a purchase.

A further object of the invention is to 25 provide a device of the character described with a base stud or die member and a top cooperating member having an aperture therein for visibly displaying therethrough a number on a ticket to be punched, so as 30 to prevent liability to making errors by punching a ticket distant from the required number.

With these and other objects in view, the 35 invention resides in certain novel constructional features, the essential characteristics of which, hereinafter fully described, and particularly pointed out in the appended claims, are illustrated in the accompanying drawing in which:

40 Figure 1 is a top plan view of my improved punching device with a ticket positioned therein.

Figure 2 is an enlarged longitudinal sectional view taken centrally thereof.

45 Figure 3 is a horizontal sectional view on the line 3—3 of Figure 1.

Figure 4 is a perspective view of a slightly modified form of the invention.

50 Referring particularly to the drawing by reference characters, the numeral 10 designates the punching device in its entirety, which includes a base plate 11, the opposite ends of which are provided with like apertures 12 to accommodate screws 13 or the like for attaching the device to any surface 55 14, such as a counter or table.

Struck up from or otherwise formed with the plate 11 is a pair of walls 15, which support an inclined platform 16, the latter being integral with said walls, while an extension 17 of the platform projects beyond the edge of the support 14. On slightly loosening the screws 13 the plate is movable in fore and aft directions for adjusting the position of the device 10 relative to the edge 60 65 of said support.

The platform 16 has a male die member or stud 18 rigidly mounted thereon, while a resilient strip 19 of suitable metal, which has an aperture 20 therein in register with said stud, is attached to the front of the platform 16, as by rivets 17, there being also a leaf spring 21 attached to the platform by 70 75 said rivets. This leaf spring, which serves as an auxiliary means for returning the strip 19 to its original position, after the latter has been depressed to punch a disk showing a number 75 from a ticket 22, is provided with a longitudinally elongated aperture 23 to allow of freedom of movement of said leaf spring during the punching 80 operation.

In order to readily admit the ticket to the punching device, I prefer to turn the terminal of the member 16 and the terminal 24 of the strips 19 in opposite directions. The stud 18 is provided with an annular cutting edge bounding its top surface, but any other form of cutting edge, such as a cross or an X may be provided without departing 85 90 from the invention.

In Figure 4, I have illustrated a slightly modified form of punch, in which a curved plate 11' is provided with slots 12' for receiving a strap of flexible material, such as leather or rubber, for removably attaching the punch to the arm or wrist of an attendant, and since the ticket may be inserted above the die member 18 and the terminals 17' and 24 operated by one hand, 95 100

the punching device requires less manipulation and is therefore more sanitary than punches as heretofore constructed.

While I have described what I deem to be the most desirable embodiment of my invention, it is obvious that many of the details may be varied without in any way departing from the spirit of my invention, and I therefore do not limit myself to the exact details of construction herein set forth nor to anything less than the whole of my invention limited only by the appended claims.

What is claimed as new is:

1. A punching device comprising lateral plate members having openings therein, said openings adapted to receive fastening elements for attaching said device adjacent the edge of a fixed structure, a pair of walls rising from said plate members, an inclined platform integral with said walls and having a rear extension adapted to be positioned above and beyond the edge of the fixed structure, a stud rigid with said platform, and a resilient strip having an aperture therein registering with said stud, one end of said strip attached to the front of said platform and the opposite end of said strip extending above and in mating relation with the rear of said platform.

2. A punching device including the combination of a sheet structure presenting oppositely extended terminal base portions, a pair of side wall portions rising from said structure between the terminal base portions, and an inclined top wall portion integral with said side wall portions and having a rear extension adapted to be positioned beyond the edge of the fixed structure; a stud rigid with said top wall portion, a yieldable strip having an aperture therein above and in registry with said stud, one end of said strip attached to the front of said platform; a spring movable vertically on said stud for resiliently urging said yieldable strip thereabove, and a manipulative portion of said strip disposed above and in mating relation with the extension of said platform, substantially as and for the purpose described.

In testimony whereof I hereby affix my signature.

LOUIS ROCHAT.
